CLAIM

(57) The ornamental design for a portable light, substantially as shown and described.

DESCRIPTION

FIG. 1 is a first side view of a portable light showing our new design;

FIG. 2 is a side view of a second side thereof;

FIG. 3 is a side view of a third side thereof;

FIG. 4 is a side view of a fourth side thereof;

FIG. 5 is an end view of a first end thereof; and,

FIG. 6 is an end view of a base end thereof.

Broken lines in the illustrations of the drawing indicate unclaimed parts of the article and/or unclaimed environment that are not part of the design herein. The portable light is a single design in which a head portion thereof may be rotatable to different positions of which examples are shown.
